(57) **CLAIM**

The ornamental design for a recharging terminal for electric vehicles as shown and described.

DESCRIPTION

FIG. 1 is a right-front perspective view of the recharging terminal for electric vehicles;

FIG. 2 is a front view thereof;

FIG. 3 is a left-front perspective view thereof;

FIG. 4 is a left-rear perspective view thereof;

FIG. 5 is a right side view thereof; and,

FIG. 6 is a rear view thereof.

The features shown in broken lines form no part of the claimed design.

1 Claim, 6 Drawing Sheets
